UNITED STATES PATENT OFFICE.

ACHILLE D. MONIOT, OF PHILADELPHIA, PENNSYLVANIA, ASSIGNOR TO WILLIAM H. MARGERISON AND ALBERT E. MARGERISON, BOTH OF PHILADELPHIA, PENNSYLVANIA.

DESIGN FOR A RUG.

41,579.

Specification for Design.

Patented July 11, 1911.

Application filed April 3, 1911. Serial No. 618,777. Term of patent 7 years.

To all whom it may concern:

Be it known that I, ACHILLE D. MONIOT, a citizen of the United States, residing at Philadelphia, in the county of Philadelphia and State of Pennsylvania, have invented a new, original, and ornamental Design for Rugs, of which the following is a specification, reference being had to the accompanying drawing, forming a part thereof.

The figure is one quarter of a rug, showing my new design the other three quarters of which are repetitions thereof.

I claim:

The ornamental design for a rug, as shown.
ACHILLE D. MONIOT.
